United States Patent Office.

JOSIAH J. MACKEY, OF SOUTH BROOKLYN, NEW YORK.

Letters Patent No. 71,772, dated December 3, 1867.

IMPROVED SPRING FOR DOORS.

The Schedule referred to in these Letters Patent and making part of the same.

TO ALL WHOM IT MAY CONCERN:

Be it known that I, JOSIAH J. MACKEY, of South Brooklyn, in the county of Kings, and State of New York, have invented a new and improved Door-Spring; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved application of a spring to doors, for the purpose of preventing the slamming of the same as they close. In the accompanying sheet of drawings—

Figure 1 is a side view of my invention.

Figure 2, a plan or top view of the same.

Similar letters of reference indicate like parts.

A represents a spring, which is formed by splitting a bar of steel, B; or said bar may be of iron or steel, forged or made separately, with the spring welded to it. The outer end of the bar B is curved or bent round, as shown at a in fig. 2; and the inner end of said bar is forged with a cross-plate, b, which is "eat in" the jamb, c, of the door-frame, and secured thereto by screws, d, the outer surface of the cross-plate being "flush" with the outer surface of the jamb c, so as to admit of the door, e, closing against the shoulder-piece, f, of the jamb, as will be understood by referring to fig. 2.

The spring A projects out from the bar B within the path of the movement of the door e, so that the door in closing will strike the spring and force it towards the bar B, the resistance of the spring being sufficient to overcome the velocity of the door before it comes in contact with the shoulder-piece f, and prevent the former from slamming.

This spring may be applied to the jamb of the door-frame, or to the top cross-piece of the frame, and even to the side piece, if desired. In general, however, the jamb of the door-frame will be the most convenient place.

Having thus described my invention, I claim as new, and desire to secure by Letters Patent—

The spring constructed as described, consisting of the parts, A B, secured to the door-frame, substantially as described and for the purpose specified.

JOSIAH J. MACKEY.
